UNITED STATES PATENT OFFICE.

ALEXANDER Y. CUNNINGHAM, OF ATTLEBORO, MASSACHUSETTS, ASSIGNOR TO THE
D. F. BRIGGS COMPANY, OF ATTLEBORO, MASSACHUSETTS, A CORPORATION OF MASSACHUSETTS.

DESIGN FOR A BRACELET.

44,556.

Specification for Design.

Patented Aug. 26, 1913.

Application filed July 5, 1913. Serial No. 777,592. Term of patent 7 years.

To all whom it may concern:

Be it known that I, ALEXANDER Y. CUNNINGHAM, a citizen of the United States, residing at Attleboro, in the county of Bristol and State of Massachusetts, have invented a new, original, and ornamental Design for Bracelets, reference being had to the accompanying drawing, in which—

The figure is a perspective view of the bracelet, showing my design.

I claim—

The ornamental design for a bracelet, as shown.

ALEXANDER Y. CUNNINGHAM.

Witnesses:

FREDERIC C. WILMARTH,
GRACE E. WILKINSON.
